PUMP

Erwin C. Horton, Hamburg, N. Y., assignor to Tri-
co Products Corporation, Buffalo, N. Y.

Application January 16, 1939, Serial No. 251,159

12 Claims. (Cl. 103—4)

This invention relates to a pump and fluid system especially adapted for use in the power plants of motor vehicles though not restricted to such use.

It has for its primary object to provide an efficient pump which is capable of providing an output pressure of greater uniformity and one which is exceedingly quiet in operation.

Another and equally important object of this invention is to combine the pump with the liquid and gaseous systems, such as the lubricating and accessory systems of a motor vehicle, in such manner as to insure greater efficiency from both systems.

In the drawings

Fig. 1 is a diagrammatic view illustrating the improved pump as used in a motor vehicle power plant;

Fig. 2 is a sectional view through the pump;

Fig. 3 is a bottom plan view of the pump as shown in Fig. 2;

Fig. 4 is a horizontal sectional view through the pump;

Fig. 5 is a top plan view of the pump as shown in Fig. 2;

Fig. 6 is a transverse sectional view taken substantially at right angles to the plane of section in Fig. 2; and

Fig. 7 is a detailed section of the eccentric piston with the by-pass valve in its fully opened position.

Referring more particularly to the drawings, the pump has a housing 11 divided into chambers 12 and 13 by an air displacing member 14 in the form of a vane-like piston which is pivotally mounted on a pin 15 for oscillatory movement. The air displacing vane or piston 14 is itself formed with a compartment in which an eccentric piston 16 operates to alternately enlarge and enlarge the chambers 17 and 18 into which the compartment is divided thereby. The eccentric piston is fixed on a drive shaft 19 having a gear 20. The housing 11 is of cup formation and has its rear or upper side, as viewed in Fig. 2, closed by a cover plate 21 which may be formed integrally with the bearing 22 in which the shaft 19 is journaled, the component sections of the housing being held together by suitable means such as screws 23.

Rotary movement of the shaft 19 will impart like movement to the eccentric piston 16 and consequential oscillatory movement to the chambered piston 14, and where the pump is used for displacing two different fluids, such as oil and gas, individual ports are provided for the differ-

ent fluids. For this purpose the back or mounting plate 21 may be provided with an inlet opening 24 leading to an inlet port 25 which is in the form of an annular recess about the shaft 19. This annular port is in substantial registry with an annular facial recess 26 in the eccentric piston 16, which communicates through a duct 27 with a radial inflow passage 28 that discharges through the periphery of the eccentric piston at the low pressure or intaking side thereof so as to discharge the liquid into the enlarging one of the two chambers 17 and 18. The pressure or forward side of the rotating piston is provided with a radial outflow passage 29 leading from the periphery of the piston and discharging through an axial passage 30 into a wall passage 31 of the pump housing, which communicates through a side wall duct 32 and thence through an outlet opening 33 in the mounting plate where delivery connection may be made. The two fluid displacing members 14 and 16 have sliding fit with the housing walls and the clearance therebetween is sealed by the liquid that is being acted upon in the chambers 17 and 18.

For the air or gas section of the pump the housing is formed with an inlet port 34 which branches into chamber passages 35 and 36 leading respectively to the air chambers 12 and 13 and each provided with a ball check valve 37 designed to effect unidirectional flow into such chambers. The air, together with any spent sealing oil, will exhaust from the chambers through outlet ports 38 and 39, past the spring seated check valves 40 therein, and discharge through canals 41 formed in the mounting plate casting, such canals being definitely contoured by a gasket 41'. Where oil is utilized as the sealing liquid the discharging liquid may be utilized to lubricate the bearing for the drive shaft 19 and for this purpose the casting is formed with opposed openings 42 to which the canals 41 lead. These openings 42 are located between machined annular mounting pads 43 about the shaft bearing 22, and when the sealing oil is delivered from the suction pump, it will first enter the openings 42 and thereafter will be blown into the surrounding chamber of the engine block, between the mounting pads, and out through an offset canal 44 in the outer pad 43. As it moves along the canal the oil will pass over an oil opening 45 to lubricate the inner end of the shaft 19 and also spray onto the gear 20 and its intermeshing drive to thoroughly lubricate such elements. In this connection it will be observed that the oil which collects in the

opening 42 will tend to flow outwardly along the shaft 19 by reason of the suction maintaining in the pump and especially in the annular recess 25 by reason of air slippage along the shaft.

For lubricating the journal support of the vane piston on the pin 15 a groove 46 is provided in one side face of the vane to establish communication between the oil chamber 17 and one end of the pin bearing. The opposite face of the piston is formed with a facial groove 47 establishing communication between the opposite end of the pin bearing and the air chamber 13. This will enable the pressure differential between the chamber 17 and the chamber 13, when under compression in the former, to cause a restricted flow of the lubricant through the groove 46, along the pin within its bearing, and out through the groove 47 into the chamber 13 where it may further serve to seal the sliding contact between the vane piston and the walls of the housing.

Wear plates 48 are provided for receiving the thrust from the eccentric piston 16. These plates or inserts are of relatively harder metal and preferably positioned at the time of die casting the vane piston. By the use of such hardened surfaces the close tolerances between the vane and its driving eccentric piston are maintained throughout the life of the pump.

From the foregoing it will be observed that the eccentric piston operates in a dual capacity, first in the direct pumping of one fluid by alternately enlarging and ensmallng the chambers 17 and 18 and secondly in the actuation of the swinging piston through the camming action of the eccentric thereon for the indirect pumping of another fluid.

It has been found that owing to the incompressibility of liquid an objectionably high pressure will develop in the chambers 17 and 18 as the eccentric piston approaches and reaches its innermost position. This subjects the parts to excessive strain and produces a pounding noise which precludes a quiet pump. To remedy this means are provided to determine the extent of pressure build-up in the oil chambers beyond a predetermined degree. This important phase of the invention is taken care of effectively by bypassing excess liquid from the pressure side of the eccentric to the intaking side thereof. The by-passing means, as depicted, comprises a by-pass 49 in the eccentric piston itself which is preferably much larger than passage 29 and discharges through a port 50 into the radial inflow passage 28, and this cross-communication is normally closed or interrupted by a check valve 51 which is designed to open the interchamber communication after a predetermined pressure build-up in the pumping or active chamber 17 or 18. The check valve is of the piston type and is arranged in an axial bore 52 in the eccentric piston 16. It is yieldably held closed by a backing spring 53 confined in the bore, such closed position being fixed by a stop pin 54. This stop pin is arranged adjacent the radial outflow passage 29 without restricting the oil flow therethrough.

The operation of this valve is such that under normal pumping the oil which is subjected to pressure in either chamber 17 or 18 will leave such chamber through the outflow passage 29 and discharge through the wall passage 31. As the piston 16 approaches its innermost position, at which time the pressure on the confined body of liquid will rise rapidly and become quite excessive, the pressure will act on the outer end of the valve 51 and force it inwardly against the

urge of spring 53 to open the by-pass whereupon the confined body of liquid, beyond that portion thereof which can be accommodated by the outlet 29 will cross over from the active chamber 17 into the companion intaking chamber along with the fresh inflowing stream which is entering through the duct 27. The communicating port 50 is offset inwardly from the passage 49 so that when the valve 51 is motivated by the liquid it will insure free communication between the passage 49 and the radial passage 29 before the bypassing action takes place. This will avoid the valve chattering against the stop pin 54 or even over the passage 49 under the pulsations of the pump.

By having the by-pass within the rotating eccentric piston the fluid cross flow is always in the same direction with respect to the direction of rotation, so that only one valve is required to control the ever reversing by-pass of liquid, such by-passing being confined between the chambers 17 and 18 and flowing first from chamber 17 to chamber 18 and then, as the rotary movement continues, from chamber 18 to chamber 17. The chamber in which the liquid is being subjected to pressure is obviously relieved in accordance with the setting of the spring 53. The by-passing valve is moved to a position entirely out of the path of fluid flow so that the full capacity of the by-passage may be utilized. The axial bore 52, behind the sliding valve, is vented into the inflowing oil stream by a bleed hole 55, and in order to add strength to the chambered vane the latter has its front and back walls braced by a connecting web 56 which is apertured at 57 to avoid interference with the delivery of the oil.

The use of the internal by-pass of the pump under conditions having large variations in speed is unique in that the pump can be given large displacement volumes in order for it to have a sufficient pump capacity at low speed and at the same time permitting the construction of the pump with inlet and outlet passages much too small to accommodate the movement of the total displacement when the pump is operating at a relatively high speed. The internal by-pass provides a means for the automatic relief of the higher pressures incidental to a restricted usage of the incompressible fluid being acted upon by the pump of the variable displacement. The relieving of this pressure is effectively accomplished by reason of the fact that the transfer of the excess displacement from one chamber to the other is over the shortest distance possible and through a by-pass having a maximum capacity considerably larger than either the inflow or the outflow ports for such chambers and while the maximum capacity is available for use it will be recognized that the valve 51 controls or regulates this capacity in accordance with the demands being made upon the pump with the result that the outlet pressure of the pump is maintained as constant as possible at all speeds of operation. The outflow passage 29 is always open while the larger by-passage is normally closed and in this connection it will be noted that the transmitted pressure on the fluid flowing out of passage 29 acts upon the adjacent end of the check or piston valve 51, and as the pressure builds up beyond the counteraction of spring 53 the valve will be moved inwardly to first uncover by-pass 49, but the delivery port 50 will not be uncovered until the valve has moved sufficiently far from the stop pin 54 to be out of danger of contact therewith as the valve responds to the

pulsations in the delivered liquid. When the valve is closed the passage 29 remains open but as the valve recedes the by-pass 49 will obviously serve for the delivery of fluid by the pump along with the passage 29. When the port 50 is uncovered, then the transfer passage 49, 50, 28 will provide greater capacity for the escape of the excess liquid than that normally provided by the smaller passage 29.

If for any reason the inner chambers 17 and 18 of the pump should become dry, as when the pump is first installed or because of the depletion of the liquid supply, it will only be necessary to operate the pump a brief interval before the replenishing liquid will again be drawn into the inner chamber. This self-priming characteristic of the pump is primarily due to the fact that even though the clearance may not be sealed, nevertheless it must be recognized that the eccentric piston is working in its chambers within an outer zone, as defined by chambers 12 and 13, which zone is of very low pressure for the greater part of the travel of the vane and consequently the air slippage is minimized to a practical extent. The displacement of the vane piston being much greater than that of the eccentric piston further insures this self-priming operation because the vane piston in effect will act to pull the oil into the pump even without the assistance of the eccentric. Obviously when the oil reaches pumping chambers 17 and 18 such liquid will seal or pack to close off the vacuum pump whereby both will operate in their normally efficient manner.

The maximum power input of the pump is kept to a minimum since the four cycle action of the pump alternates the liquid and air displacing operations. For example when the liquid is being subjected to its greatest pressure the vane piston is midway between two limits of movement and similarly when the vane piston is exerting its greatest pressure the eccentric piston is midway between its opposite limits of compression.

The multiple pump unit has a wide range of use and is admirably adapted for automotive purposes, as generally indicated in Fig. 1, wherein the pump is piped into the lubricating system of a motor vehicle power plant with the inlet 24 connected by conduit 58 to the oil crank case sump or reservoir and its outlet 33 delivering through conduit 59 to the several points of lubrication in the system.

The air inlet port 34 may be connected by a tube 60 to a suction operated accessory, such as the windshield cleaner 61. By reason of the vane having a greater fluid displacing capacity, as compared with the eccentric piston, the accessory will be insured a constant and ample supply of low pressure for efficient operation.

While the foregoing description has been given in detail, it is obvious that the inventive principles herein involved may assume other physical embodiments without departing from the spirit of the invention set forth and claimed.

What is claimed is:

1. A pump having a compartment with opposed contact surfaces in its sides between opposed end chambers, a rotary piston having its periphery constantly bearing on the surfaces to seal the two chambers one from the other, means eccentrically mounting the piston for movement of its periphery to ensmall and enlarge the two chambers in succession for fluid displacing action therein, means for rotating the piston, inlet

and outlet means for the chambers, a transfer passage through the piston from the chamber ensmalling side to the chamber enlarging side thereof for by-passing excessive displacement from both chambers in succession, said transfer passage having greater capacity than the outlet means and acting to transfer fluid back and forth between the two chambers, and valve means for regulating the transfer of fluid through said passage to determine a maximum pressure on the pump output.

2. A pump having a compartment with opposed contact surfaces in its sides between opposed end chambers, a rotary piston having its periphery constantly bearing on the surfaces to seal the two chambers one from the other, means mounting the piston for movement of its periphery in an eccentric path to ensmall and enlarge the two chambers for fluid displacing action therein, means for rotating the piston, a transfer passage through the piston from the chamber ensmalling side to the chamber enlarging side thereof and acting first to permit excess fluid movement from one chamber to the other and then a reverse movement but always in the same direction through the passage, a spring pressed valve normally closing the passage and responsive to a predetermined pressure of the pump delivery for movement from the passage, inlet means for the chambers, and outlet means from the chambers having operative communication with the valve independently of the transfer passage to render the valve pressure responsive.

3. A pump having a housing, a fluid displacing member therein movable back and forth between the side walls thereof for fluid displacement and itself provided with a compartment elongated in a direction transversely of the path of movement, a rotatable piston eccentrically journaled in the side walls of the housing and operating in the compartment to cam against the opposing sides thereof for imparting such back and forth movement to the fluid displacing member, the piston having a diameter substantially equal to the spacing of the opposing sides of the elongated compartment and serving to divide and seal the opposite ends of the compartment one from the other, said piston by reason of its eccentric mounting moving into and out of the ends of the compartment for fluid displacing action, means for rotating the piston, inlet and outlet means for the housing, inlet and outlet means for the opposite ends of the compartment, and means for by-passing excess fluid displacement from the high pressure side to the low pressure side of the rotatable piston first from one end of the compartment to the other and then, after a half turn of the rotatable piston, from the other end of the compartment to the first specified end thereof.

4. A pump having a housing, fluid inlet and outlet means for said pump, a piston mounted therein for movement between and in sliding contact with opposing side walls of the housing, said piston formed with an elongated compartment extending transversely of its path of movement and closed by the side walls, a rotary piston journaled eccentrically in the side walls and operating in the compartment to displace fluid from the opposite ends of the compartment, the rotary piston having a diameter substantially equal to the spacing of the sides of the compartment and acting in the capacity of an eccentric to impart back and forth movement to

the first piston, a web joining the opposing sides of the compartment across one end of the rotary piston and having an opening in registry with a wall passage of the housing, said rotary piston having a fluid port communicating through the web opening with the wall passage and forming a part of said inlet and outlet means for the pump, and means for operating the rotary piston.

5. A pump having a movable casing with a compartment having opposing side walls joining opposing end chambers, a rotatable piston mounted in the compartment and having an eccentric peripheral surface contacting the side walls and operable to alternately enlarge and ensmall the opposite end chambers in succession for intaking and expelling fluid from each, bypass means within the rotatable piston leading from the delivery side of the piston to the intaking side thereof, said bypass means being normally closed and responsive to a predetermined fluid pressure successively first in one end chamber and then in the other end chamber for opening to transfer excess displacement from the end chamber at the delivery side of the piston to the other end chamber at the intaking side of the piston, and inlet and outlet passages for admitting and exhausting fluid from the end chambers of the pump.

6. A pump comprising a housing having a journal pin therein, an oscillating member pivoting on the pin for gas displacing operation in the housing and itself formed with a liquid chamber, said member dividing the interior of the housing into fore and aft gas chambers which are alternately ensmallled and enlarged by said member for the displacement of gas, a rotary cam operating in the liquid chamber of said member and having peripheral contact with two opposing sides of the liquid chamber for oscillating the member and functioning additionally to displace liquid from the liquid chamber, means for rotating the cam, and inlet and outlet means for the several chambers, there being a liquid duct leading from the liquid chamber of said member to the journal pin adjacent one end and a second duct leading from adjacent the opposite end of the journal pin to one of said gas chambers for the flow of liquid about the pivotal mounting of said member to lubricate such pivotal mounting.

7. A pump comprising a housing with a compartment having opposed contact surfaces interposed between opposed end chambers thereof, a rotary fluid displacing member having an eccentric periphery in bearing contact with such surfaces and separating the two chambers while the periphery ensmalls and enlarges the chambers, means supporting the housing and member for relative movement during rotation of the displacing member, means for rotating the latter, inlet and outlet means for the chambers, a transfer passage in the rotary displacing member opening through the periphery at opposite sides thereof, each end of the passage opening successively into the opposed chambers for relieving excessive displacement from the delivery side to the intaking side of the rotary displacing member by transferring fluid first from one chamber to the other and then reversely from said other chamber to said one chamber as the pressures in the two chambers successively become predominant but always in the same direction of flow through the transfer passage, and a one-way spring-seated check valve normally closing the transfer passage and responsive to a predetermined pressure at

the delivery side of the rotary displacing member for opening to permit such fluid transfer.

8. A pump for the combined pumping of two fluids, one, gas and the other liquid, comprising a housing having fore and aft chambers, a piston movable back and forth in the housing for the displacement of gas from the chambers and itself formed with a compartment having opposed front and back side wall portions, a circular piston arranged in the compartment and journaled eccentrically in the housing, means for rotating the circular piston, said circular piston having its eccentric periphery of a diameter substantially equal to the space between the opposed side wall portions for camming thereon to impart the back and forth movement to the first piston, said circular piston operating during its rotation to displace liquid first from one end of the compartment and then from the other end thereof, inlet and outlet passages for the chambers and the compartment, the circular piston having a passage therethrough opening at its opposite ends simultaneously into the opposite ends of the compartment for the transfer of excess liquid from the delivery side of the circular piston to the intaking side thereof first from said one end of the compartment to said other end thereof and then from the latter end thereof to the first end of the compartment, and means for controlling the by-passing capacity of the transfer passage whereby the displacing action of the circular piston is regulated to substantial uniformity so that the displacing action of the first piston is substantially uniform.

9. A pump for the combined pumping of two fluids, one gas and the other liquid, comprising a housing having fore and aft chambers, a piston movable back and forth in the housing for the displacement of gas from the chambers and itself formed with a compartment having opposed front and back side wall portions, a circular piston arranged in the compartment and journaled in the housing for eccentric rotation about an axis, means for rotating the circular piston, said circular piston having a diameter substantially equal to the space between the opposed side wall portions with its eccentric periphery camming on the side wall portions to impart the back and forth movement to the first piston, said circular piston operating during its rotation to displace liquid first from one end of the compartment and then from the other end thereof, inlet and outlet passages for the chambers and the compartment, the circular piston having a passage therethrough opening at its opposite ends simultaneously into the opposite ends of the compartment for the transfer of excess liquid from the delivery side of the circular piston to the intaking side thereof first from said one end of the compartment to said other end thereof and then from the latter end thereof to the first end of the compartment, and a self-closing valve normally closing the transfer passage and responsive to a predetermined delivery pressure in the compartment to open the passage for the transfer of excess fluid through the circular piston.

10. A pump comprising a housing with a compartment having opposed contact surfaces joining opposed end chambers thereof, a rotary fluid displacing member having an eccentric periphery in bearing contact with such surfaces and separating the two chambers while the periphery ensmalls and enlarges the chambers, means supporting the housing and member for relative movement during rotation of the displacing

member, means for rotating the latter, inlet and outlet means for the chambers, a transfer passage in the rotary displacing member opening through the periphery at spaced points so arranged that each end of the passage opens successively into the opposed chambers for relieving excessive displacement from the delivery side to the intaking side thereof by transferring fluid first from one chamber to the other and then reversely from said other chamber to said one chamber as the pressures in the two chambers successively become predominant but always in the same direction of flow through the transfer passage, and means for controlling the by-passing capacity of the transfer passage including a valve carried by said rotary displacing member and movable back and forth on the axis of rotation thereof, whereby to be unaffected by centrifugal influence during the rotation of said rotary displacing member, said valve being responsive to the fluid pressure at the delivery side of the rotary displacing member.

11. A pump comprising a housing with a compartment having opposed contact surfaces joining opposed end chambers thereof, a rotary fluid displacing member having an eccentric periphery in bearing contact with such surfaces and separating the two chambers while the periphery en-smalls and enlarges the chambers, means supporting the housing and member for relative movement during rotation of the displacing member, means for rotating the latter, inlet and outlet means for the chambers, a transfer passage in the rotary displacing member opening through the periphery at spaced points so arranged that each end of the passage opens successively into the opposed chambers for relieving excessive displacement from the delivery side to the intaking side thereof by transferring fluid first from one chamber to the other and then reversely from said other chamber to said one chamber as the pressures in the two chambers successively become predominant but always in the same direction of flow through the transfer

passage, said rotary displacing member being formed with a valve chamber arranged on the axis of rotation and communicating with the transfer passage, and a valve arranged in the 5 valve chamber and movable back and forth in an axial direction for regulating the by-passing capacity of the transfer passage, said valve being responsive to fluid pressure at the delivery side of the rotary displacing member free and independent of centrifugal influence.

12. A pump comprising a housing with a compartment having opposed contact surfaces joining opposed end chambers thereof, a rotary fluid displacing member having an eccentric periphery in bearing contact with such surfaces and separating the two chambers while the periphery en-smalls and enlarges the chambers, means supporting the housing and member for relative movement during rotation of the displacing member, means for rotating the latter, inlet and outlet means for the chambers, transfer passage means in the rotary displacing member opening through the periphery at spaced points and so arranged that the passage means opens successively into the opposed chambers for relieving excessive displacement from the delivery side to the intaking side thereof by transferring fluid first from one chamber to the other and then reversely from said other chamber to said one chamber as the pressures in the two chambers successively become predominant but always in the same direction of flow through the transfer passage means, and valve means for controlling the by-passing capacity of the transfer passage means including a valve carried by said rotary displacing member substantially on the axis of rotation thereof whereby the centrifugal influence developed in the rotary displacing member during rotation thereof will be substantially nil on the valve, said valve being responsive to the fluid pressure at the delivery side of the rotary displacing member.

ERWIN C. HORTON.
